UNITED STATES PATENT OFFICE.

VIOLA G. GURNEE, OF NEWARK, NEW YORK.

DESIGN FOR A CANDLE.

Application filed April 3, 1922. Serial No. 1,521. Term of patent 3½ years.

To all whom it may concern:

Be it known that I, VIOLA G. GURNEE, a citizen of the United States of America, residing at Newark, in the county of Wayne and State of New York, have invented a new, original, and ornamental Design for a Candle, of which the following is a specification, reference being had to the accompanying drawing, forming part thereof.

The figure is a side elevational view of a candle, showing my new design.

I claim:—

The ornamental design for a candle, as shown.

VIOLA G. GURNEE.
